ASHPIT DOORFRAME

William J. Groth, Los Angeles, Calif.

Application November 3, 1937, Serial No. 172,537

4 Claims. (Cl. 72—101)

This invention relates to a closure for ashpits and more particularly pertains to a frame for ashpit doors of the character designed to be set in the brick work of fireplace chimneys.

An object of the invention is to provide a construction in the doorframe whereby the setting of the frame in brick work during the erection of a chimney will be greatly facilitated; such frames as now generally constructed being difficult to set in place by reason of lack of adequate means for effecting anchorage of the frame in the mortar employed in laying the bricks.

Another object is to provide a construction in an ashpit doorframe for effecting anchorage of the frame in the mortar joint between adjacent layers of brick and whereby the frame may be readily disposed in a properly aligned position.

Another object is to provide an arrangement of slots in the side members of the door frame for the reception of headed pins for the purpose of positioning the shanks of said pins in the mortar joint between one or more courses of brick and in which the pin receiving slots are so formed and arranged as to facilitate positioning of the pins in alignment with such mortar joints.

A further object is to provide the side members of the frame with protruding anchoring pins mounted for adjustment longitudinally of the frame side members.

With the foregoing objects in view, together with such other objects and advantages as may subsequently appear, the invention is carried in to effect as illustrated by way of example in the accompanying drawing in which:

Fig. 1 is a perspective view of the ashpit closure as seen from the rear or inner side thereof depicting the manner of forming the doorframe in accordance with the invention;

Fig. 2 is a view in horizontal section taken on the line 2—2 of Fig. 1 showing the closure as set in brick-work;

Fig. 3 is a view in vertical section as seen on the line 3—3 of Fig. 2;

Fig. 4 is a view in end elevation of a modified form of the doorframe.

Referring to the drawing more specifically A indicates generally the frame of a fireplace ashpit closure, which frame is rectangular in form and embodies a front wall 5 formed with rearwardly extending upper and lower flanges 6 and 7 and end flanges 8 and 9, which flanges protrude from the inner margin of the frame thus forming the latter with an outwardly opening right

angled cross section. The frame thus formed is fitted with a door B inclosed thereby which is mounted to swing horizontally relative to the frame on hinges 10 and 11. The frame and door construction above described is that commonly employed in ashpit closures now generally in use; the parts being ordinarily formed of cast metal and dimensioned relative to standard sizes of bricks employed in the erection of fireplace chimneys so as to facilitate building of the frame 10 into the chimney brick-work in forming an ashpit outlet.

The essence of the present invention resides in forming each of the end flanges 8 and 9 with a longitudinally extending elongated slot C of a length slightly exceeding the thickness of a brick, and in providing headed pins D, such as ordinary wire nails, for loose insertion through the slots C during assemblage of the frame A in a brick wall in such fashion as to form an anchorage which will serve to securely hold the frame in place in proper alignment with the courses and outer faces of the brick wall both during and after erection thereof.

The elongated slots C are so arranged that when the lower flange 7 of the frame is seated on a course of brick and bricks of a succeeding course are abutted against the end flanges of the frame, pins D inserted through the slots C may be readily positioned to overlie the abutting bricks and may be seated thereon. This is accomplished by disposing the lower ends of the slots less than the thickness of a brick from the flange 7. Likewise the slots C are of such length as to extend across one or more joints between adjacent courses of brick so as to enable positioning of pins D to project into such joints.

The slots C may be formed in the flanges 8 and 9 as by molding or cutting them therein, or may be formed as shown in Fig. 4 by a length 40 of wire 17 arranged in spaced parallel relation to the end flange and having inturned end members 18 engaged in the end flange as by casting the latter around the end members 18 or by inserting the end members in holes drilled in the 45 edge of the flange.

In the application and operation of the invention the frame A is initially positioned with the lower flange 7 thereof seated on a layer of mortar 12 spread on top of a course of brick 13, as 50 particularly shown in Fig. 3, and with the outer wall 5 of the frame overlying and abutting the outer face of the course of brick 13 in alignment therewith. A pair of bricks 14 are then set in the mortar 12 at the opposite ends of the frame 55

- A and are positioned to abut against the end flanges 8 and 9 of the latter; the bricks 14 being properly aligned for permanent setting in the wall. Pins D are then passed through the slots 5 C from the inner sides of the end flanges 8 and 9 with their heads abutting the inner faces of the flanges and with their stems lying on the bricks 14. A layer of mortar is then applied to the bricks 14 to imbed the pins D therein whereupon 10 bricks 15 of a following course are set in place to rest on the mortar joints in which the pins D are imbedded.
- A succeeding layer of brick 16 is then laid on 15 the mortar on the bricks 15 and pins D are passed through the slots C and imbedded in the mortar joint between the bricks 15 and 16. The following courses of brick are set in place in the usual manner to surround the frame A in the chimney brick-work.
- 20 An important feature of the invention resides in the fact that on initially setting the frame A in place on the mortar layer 12, then disposing the end bricks 14 in place against the end flanges 8 and 9 of the frame, and then imbedding the pins D in the mortar imposed on the bricks 14, the frame A will be self-supported so as to relieve the brick layer of the necessity of holding the frame in place until the succeeding layers of brick 15 and 16 are set in place; the lower 25 pins D then affording sufficient anchorage to retain the frame A in a properly aligned position.

By forming the slots C of a length exceeding the thickness of a brick and with their lower ends spaced from the lower flange 7 a distance less 30 than the thickness of a brick, the pins D may be readily disposed in a proper position to align with the mortar joints between contiguous courses of the brick, whether the frame be set on a full brick course as shown in the drawing or 35 on a split course.

I claim:

1. A frame for ashpit doors having a lower flange and end flanges, each of said end flanges having through it a slot which extends longitudinally said slot being of a length exceeding the thickness of a brick and the lower end of said slots being spaced from said lower flange a distance less than the thickness of a brick, and loose pins insertable through said slots and adjustable longitudinally of them for positioning in mortar joints between courses of brick-work, said mortar joints extending into the brick-work from a wall surface abutting said end flanges.
2. In a furnace structure, a door frame having 45 a lower flange and end flanges, each of said end flanges having through it a slot which extends

longitudinally thereof, said slot being of a length exceeding the thickness of a brick and the lower end of said slot being spaced from said lower flange a distance less than the thickness of a brick, courses of brick work having mortar spaces 5 between them, the outer ends of said mortar spaces being in an abutting relation to said frame, there being mortar in said spaces, and pins in said slots and projecting into said mortar spaces in parallel relation to said courses of 10 brick.

3. In a furnace structure, a door frame having a lower flange and end flanges, each of said end flanges having through it a slot which extends longitudinally thereof, said slot being of a length 15 exceeding the thickness of a brick and the lower end of said slot being spaced from said lower flange a distance less than the thickness of a brick, courses of brick work having mortar spaces between them, the outer ends of said mortar spaces being in an abutting relation to said frame, there being mortar in said spaces, and pins in said slots and projecting into said mortar spaces in parallel relation to said courses of 20 brick; said pins having heads of greater diameters than the width of said slots to limit the extent to which said pins may be projected into 25 said mortar spaces.

4. An ashpit doorframe including a wall having in it an opening bordered at its sides by superimposed courses of brick having mortar containing spaces between adjacent of said courses leading to said opening and the lower margin of which opening is bordered by a lower course on which said side courses are supported, a metallic 35 door frame having a lower flange adapted to be supported by said lower course and also having end flanges arranged to extend in close proximity to the sides of said opening in parallel relation thereto, each of said end flanges having a vertically extending slot leading through it the length of which exceeds the thickness of a course of the brick embodied in said wall, said slot being arranged in said frame to position its end portions extended beyond opposed sides of superimposed 45 mortar containing spaces in the brick courses at the sides of the wall opening, pins extending through each of said slots from the inner sides of said end flanges having outer end portions projecting into spaced mortar containing spaces at 50 the sides of the wall opening, and heads on said pins having diameters exceeding the width of said slots and abutting the inner margins of said slots.
